CLAIM

The ornamental design for a welding torch handle, as shown and described.

DESCRIPTION

FIG. 1 is a top, front and left side perspective view of a welding torch handle, showing my new design;
FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 7; and,

FIG. 10 is an enlarged view of portion 10 in FIG. 8.

The evenly dashed broken lines illustrate features of the welding torch handle that form no part of the claimed design. The unevenly dashed broken lines define the boundaries of enlarged views and form no part thereof. The dot-dash broken lines in FIG. 1, FIG. 3, FIG. 7 and FIG. 9 define the bounds of the claim and form no part thereof.
